STRAP FASTENER

Louis Maus, Baldwin, N. Y.

Application April 9, 1934, Serial No. 719,652

8 Claims. (Cl. 24—69)

This invention relates generally to strap fasteners, and more particularly to those of the class applicable to shoes, garment-supporting belts, and gloves.

5 One object of the invention is to provide means whereby the strap tension may be readily and accurately adjusted and re-adjusted.

Another object is the provision of strap-fastening means more quickly and easily operable than 10 are fasteners of present types.

A further object is the provision of strap-fastening means so constructed and arranged that it is unnecessary to weaken the strap by perforating it.

15 A still further object is the provision of a strap-fastener which, when applied to women's shoes or gloves, readily lends itself to wide variations in ornamentation for style purposes.

A still further object is to eliminate the loose 20 strap end, which, with certain other types of fasteners, projects beyond the fastening point so far that it requires to be passed through a loop in order to hold it in position.

Customarily, shoe straps are fastened either 25 by means of a button sewed or riveted to one strap and co-operating with a button-hole formed in the other strap; or by means of a so-called harness type buckle, attached to one strap and having a tongue which enters one or other 30 of a series of perforations formed in the other strap.

The button-strap shoe is initially fitted by removing the button from the strap and re-attaching it in a position to give the desired tension over 35 the instep. Should the straps stretch with use or should the foot swell, this tension necessarily changes, and it can be restored only by detaching, re-locating, and re-attaching the button.

With the harness-buckle type of fastener, it is 40 often necessary, in order to obtain the desired strap tension, to punch an additional hole through the perforated strap, which decreases its durability—particularly when it is made of silk or other delicate material.

45 When applied to women's shoes, both the button type and the harness-buckle type of fastener are objectionable in that the perforated strap is necessarily weakened; and this weakening limits the minimum width of strap which, from considerations of style, it may be desired to employ.

The button type of fastener is further objectionable because of the fact that, with the button so located that the strap is comfortably tight, it is difficult, without the use of a button-hook, to 50 draw the button into the button-hole. Moreover,

this type of fastener does not lend itself to ornamentation.

When applied to shoes, belts or gloves, the harness-buckle type of fastener is open to the further objection that the end of the perforated strap necessarily projects beyond the point where the tongue enters a perforation. This projecting end is not only unsightly, but it must be held in place by passing it through a loop provided for that purpose. 5

Fasteners of the frictional type are unsatisfactory when applied to leather straps, for the reason that the flesh side of the leather soon becomes glazed, so greatly reducing the friction between the fastener and the leather that the 10 gripping action becomes inadequate.

The present invention overcomes these and other objections inherent in strap-fastening devices now employed on shoes, belts and gloves.

The invention provides a strap fastener one 20 member of which is readily adjustable longitudinally of the strap end on which it is mounted, so that both the initial adjustment and any re-adjustment which subsequently may become necessary can be made quickly and with nicety. 25

This invention renders it unnecessary to perforate either of the shoe straps, thus obviating the weakening thereof and permitting of the use of straps of a desired narrow width.

With this invention, the strap ends may be 30 much more conveniently fastened in position and unfastened than with either the button or the harness-buckle type of fastener.

Another advantageous feature of the invention is that, for application to women's shoes 35 or gloves, the clasp element thereof permits of widely-varying kinds of ornamentation—as by embossing or enameling the same or employing it as a mounting for brilliants, semi-precious stones, or decorative devices formed of mouldable material. 40

With this invention, the strap is subjected to no frictional wear, all wear being confined to the metal parts.

The invention will best be understood by reference to the accompanying drawing, wherein is illustrated the present preferred embodiment thereof as applied to strap shoes. 45

Fig. 1 is a fragmentary top plan view showing a portion of a woman's shoe, attached to the 50 straps of which are the two members comprising the invention, as they appear in fastened position.

Fig. 2 is a longitudinal sectional view, on an enlarged scale, showing portions of two strap ends, attached to which, respectively, are the two 55

members of the invention, as they appear in unfastened position.

Fig. 3 is a view similar to Fig. 2, but showing the two members of the invention as they appear in fastened position.

Fig. 4 is a front elevation, partly in section, and on an enlarged scale, illustrating the clasp-assembly member of the device disengaged from the eye member thereof and with the strap cut away to show the means for clamping the clasp assembly to the strap.

Fig. 5 is a plan section, on an enlarged scale, on the line 5—5 of Fig. 4, viewed in the direction indicated by the arrows.

Fig. 6 is a fragmentary perspective view showing a modified form of means for holding the clasp portion of the device in fastened position.

Like reference characters indicate like parts throughout the drawing.

Referring to the drawing: An eye member 1, which may be of any suitable shape, is adapted to be attached, in any well-known manner, to an end of a strap 2. Adapted to be adjustably mounted on the opposite strap end 3 is a co-operative clasp assembly, indicated generally by the reference numeral 4. This clasp assembly includes a yoke 5, constructed and arranged to embrace the strap end 3. Mounted in the arms of this yoke is a pintle 6, which supports two bearings, 7 and 7a, formed in a plate 8. One end of this plate is bent downwardly at a substantially right angle to the body thereof, as shown in Figs. 2, 3 and 4. Formed in the end of this downwardly-projecting portion are serrations, such as 9 (Figs. 2, 3 and 4). In the clamped position shown in Figs. 2, 3 and 4, the plate 8 has been turned on the pintle 6 into a position where the serrations so engage the strap end 3 as firmly to grip it between said serrations and the body of the yoke 5. Referring to Figs. 2 and 3: when the plate 8 is turned upwardly on pintle 6, the serrations are released from engagement with the strap end 3, permitting the clasp assembly 4 to be moved along the strap to any desired position. When such position is reached, the plate 8 is then turned downwardly, i. e., to the left as shown in Figs. 2 and 3, until the serrations are again brought into clamping engagement with the strap end 3. Thus, the clasp assembly 4 may be adjusted longitudinally of the strap end 3 to provide any desired strap tension.

Formed integrally with the plate 8 and at the end thereof opposite that which has just been considered, are two upwardly-projecting lugs, 10 and 10a (Figs. 2, 3 and 4), which support the ends of a pintle 11 (Figs. 2 and 3). Embracing this pintle 11 (Figs. 2 and 3) is a tubular portion 12, formed integrally with the clasp proper, 13, of the clasp assembly 4. Formed on this tubular portion 12 is a cam 14 (Figs. 2 and 3). This cam co-operates with a spring 15 (Figs. 2, 3, 4 and 5) in the following manner: When the clasp 13 is in the unfastened position, the spring 15 is unflexed, as shown in Figs. 2 and 4. When the clasp 13 is brought into fastened position (Fig. 3), the cam 14 flexes the spring 15, thereby applying pressure to the clasp and holding it in fastened position until it is released therefrom by manually raising the clasp.

A pocket for the spring 15 is formed by lugs 10 and 10a; by projections 16 and 16a—the latter being shown in Fig. 4 as partially broken away; and by a ridge 17 (Figs. 2, 3 and 5), formed in the plate 8.

The edges of the clasp 13 are bent inwardly at

a substantially right angle to the body thereof, and are of a contour to constitute them cams, such as 18 (Figs. 2 and 3).

Referring now to Fig. 2: When the end of the clasp 13 is inserted in the eye member 1, and the end which projects therethrough is moved to the right, the eye member 1 is drawn along these cams (such as 18), progressively increasing the strap tension until said eye member is finally carried to its extreme downward position, where it bears against lugs 10 and 10a (Fig. 3). It is retained in said position by the clasp 13, which is kept fastened by the hereinbefore-described pressure of spring 15 against cam 14 of said clasp.

Referring now to Fig. 6: In lieu of spring 15 shown in Figs. 2, 3, 4 and 5, the end of plate 8 may be slotted as indicated by reference characters 19 and 19a, and the tongue 20 which is thereby formed may be employed as a spring. In this modification, the cam for flexing said spring consists of a downwardly-projecting portion 21, formed on the end of the clasp 13. The portions of the end of the clasp 13 either side of said cam 21 are bent to form tubes, such as 22, which embrace the pintle 11.

The invention may be applied to a garment-supporting belt by attaching the eye member 1 to one end of the belt, and mounting the clasp assembly 4 on the opposite end thereof.

It may be applied to a glove by attaching to one of the sides which define the opening thereof of a short strap for carrying the clasp assembly 4.

While I have illustrated and described the present preferred embodiment of the invention, I do not intend to be understood as limiting myself to this construction. It will be obvious to those skilled in the art that, without departing from the principle of the invention, it may be embodied in other forms than that which is illustrated in the drawing and described in the specification.

I claim:

1. In a strap fastener, the combination of an eye member attached to one strap end, a clasp member co-operative with said eye member, and a cam member operating independently of said clasp member for clamping said clasp member to another strap end, said clasp member and said cam member being adjustably movable along said second strap end.

2. In a strap fastener, the combination of an eye member attached to one strap end, a clasp member co-operative with said eye member, and a serrated clamp operable independently of said clasp member to attach said clasp member to another strap end, said clasp member and said clamp being adjustably movable along said second strap end.

3. In a strap fastener, the combination of an eye member attached to one strap end, a clasp member co-operative with said eye member, and a hinged clamp separately operable from said clasp member to attach said clasp member to another strap end, said clasp member and said clamp being adjustably movable along said second strap end.

4. A strap fastener comprising an eye member attached to one strap end, a hinged clasp member co-operative with said eye member, and a separately operable cam member for clamping said clasp member to another strap end, said clasp member and said clamping means being adjustably movable along said second strap end.

5. In a strap fastener, the combination of an eye member attached to one strap end, a clasp

member co-operative with said eye member, means for holding said clasp member in fastened position, and means separately operable from said clasp member and said holding means for attaching the clasp member to another strap end at any desired point thereon, said clasp member and said attaching means being adjustably movable along said second strap end.

5. In a strap fastener, the combination of an eye member attached to one strap end, a hinged clasp member co-operative with said eye member, a supporting plate for said clasp member adjustably movable along the other strap end, a hinged clamp on said supporting plate for attaching the 10 same to said second strap end, a spring on said supporting plate, and a cam on said clasp member for flexing said spring to hold the clasp member in fastened position.

15. In a strap connector, the combination with an eye secured to one strap end of a clasp as-

sembly adjustably secured to another strap end, said clasp assembly comprising a pair of hingedly connected clamping members adapted to be turned into strap gripping relation, and a clasp hingedly mounted on one of said clamping members for receiving and retaining the eye.

10. In a strap connector, the combination with an eye secured to one strap end of a clasp assembly adjustably secured to another strap end, said clasp assembly comprising a pair of hingedly connected clamping members adapted to be turned into strap gripping relation, and a clasp hingedly mounted on one of said clamping members for receiving and retaining the eye, said clasp 15 having a cam extension, and the clasp-carrying clamping member having a spring tongue cooperative with the cam extension to hold the clasp in closed position.
